(57) **CLAIM**

The ornamental design for an armored vehicle as shown and described.

DESCRIPTION

1.1 : is a front elevation view of an armored vehicle embodying our new design;

1.2 : is a rear elevation view thereof;

1.3 : is a left side elevation view thereof;

1.4 : is a right side elevation view thereof;

1.5 : is a top plan view thereof;

1.6 : is a top, front and right side perspective view thereof; and

1.7 : is a top, rear and left side perspective view thereof. The design relates to an armored vehicle; the broken lines shown are for illustrating portions of the armored vehicle forming no part of the claimed design.

1 Claim, 7 Drawing Sheets
